UNITED STATES PATENT OFFICE.

NELSON K. SMITH, OF DALLAS, TEXAS.

PIPE WRENCH.

Application filed February 12, 1924. Serial No. 692,204.

To all whom it may concern:

Be it known that I, NELSON K. SMITH, a citizen of the United States of America, residing at Dallas, in the county of Dallas and

5 State of Texas, have invented certain new and useful Improvements in Pipe Wrenches, of which the following is a specification.

This invention relates to new and useful improvements in pipe wrenches.

10 The principal object of the invention is to provide a pipe wrench for use in connection with the rotary system of drilling wells, and particularly for connecting and disconnecting the sections of pipe and tool joints in a simple, expeditious, and safe manner.

A particular object of the invention is to provide an improved pipe wrench which may be automatically locked around a pipe and which when gripping the pipe and under a 20 severe strain will not spread or break.

A further object is to provide a safety latch which automatically locks the wrench on the pipe and holds said wrench in position until the latch is released.

25 Another object is to provide in combination with a yoke, a swinging gripping arm having a pipe-engaging finger which serves to close the arm when the pipe is received in the yoke and also functions to displace the pipe from the yoke when the arm is swung into an open position.

A still further object of the invention is to provide a tension element within the yoke which has the dual function of latching or 35 holding the handle in an open position and of forcing the pipe against the gripping faces of the wrench.

Another object of the invention is to provide a gripping arm and a swinging handle 40 cooperating with a yoke in such a manner as to grip the pipe in a positive manner.

Constructions designed to carry out the invention, together with other novel features, will be hereinafter described.

45 The invention will be more readily understood from a reading of the following specification, and by reference to the accompanying drawings in which examples of the invention are shown and wherein:

50 Fig. 1 is a plan view of a wrench constructed in accordance with my invention, the wrench being shown in full lines engaged around a pipe and in its open position in dotted lines;

55 Fig. 2 is a sectional view on the line 2—2 of Fig. 1;

Fig. 3 is a side elevation of the wrench engaged on a pipe; and

Fig. 4 is an enlarged cross-sectional view on the line 4—4 of Fig. 1.

In the drawings, the numeral 10 designates an arcuate yoke having a concave gripping face or seat 11. The yoke is provided at one end with a pair of superposed ears 12, and at its opposite end it has a larger pair of superposed ears 13. A swinging arm 14 is fulcrumed between the ears 12 on a bolt 15 and is provided with an inwardly extending finger 16 adapted to swing from between said ears into the opening of the yoke, when said arm is swung to its open position, whereby said finger is positioned in the path of the pipe A. When the pipe is received in the yoke, it engages the finger 16 and swings the arm to a closed position. The arm is provided with a hand-grip 17 whereby it may be swung outwardly to an open position, as is indicated in dotted lines in Fig. 1. When the arm is opened, the finger 16 swings in behind the pipe and dis- 70 places the same from the yoke.

A handle lever 18 is pivoted on a bolt 19. The handle has at its inner end a notch or seat 20 for receiving a boss 21 projecting outwardly from the free end of the arm 14. The arm 14 is provided with a notch or recess 22 contiguous to the boss for receiving a lug 23 on the end of the handle. It will be noted that the lug 23 engages over the boss 21, to such an extent as to co-act with the bolt 19, in holding the ends of the yoke against spreading.

The arm 14 is comparatively short and swings through a short radius; this with the rigid reinforced yoke makes for a strong structure which is not likely to break under a severe strain. The yoke 10 has a pair of gripping dies 25, while the arm is provided with a similar die 26; however the location and number of the dies is subject to variation, and they are quite common in this art.

It is evident that when the arm 14 is in its open position, it is desirable to hold the handle lever 18 in its open position so that it will not interfere with the placing of the yoke on the pipe, and for this purpose, I mount a tension dog 27 in a recess 28 in the yoke. This dog is mounted on a pin 29 and has a lug 30 adapted to engage in a notch 31 in the inner end of the handle when the latter is swung to its open position. The dog is impelled into such engage- 105

ment by a coiled spring 32 which tends to force the nose 33 of the dog through the seat 11 of the yoke. When the dog is in engagement with the handle, the nose 33 is 5 in the path of the pipe. The dog tends to force the pipe into the seat 11 and acts to take up play, whereby the wrench more quickly grips the pipe. When the handle is ready to be swung, the pipe will have 10 previously depressed the dog, whereby the lug 30 is removed from the notch 31, and said handle may be freely swung.

A short rigid handle 34 extends outwardly from the intersection of the arm 14 and 15 the finger 16 at the bolt 15. This handle is useful in swinging the arm when necessary, and in manipulating the wrench. The wrench is designed for use either on the upper or lower members of a tool joint, or on 20 a pipe, and may also be supported in a rotary table carriage such as is shown in Letters Patent Nos. 1,481,157, and 1,481,158, issued to me on Jan. 15, 1924.

One of the important features of this invention resides in means for latching the 25 arm 14 in its closed position, so that said arm can not become accidentally disengaged or otherwise interfere with a safe manipulation of the wrench. For this purpose, the 30 handle 34 is provided with a longitudinal slot 35 having its inner end extending between the ears 12, as is best shown in Fig. 2. A latch lever 36 is pivoted in said slot and is provided with an inwardly extending 35 shank 37 having a lug 38 on its inner end. The latch lever is overbalanced so that the shank tends to fall through the slot, whereby the lug 38 comes to rest on the lower ear 12. The ears each have a shoulder 12'. When the shank 37 drops through 40 the slot, the lower shoulder 12' will be in its path and permits only a limited swinging movement of the arm 14. When the wrench is reversed, the latch lever is inverted 45 so that the other lug 12' is used. The latch has a boss 39 on the opposite side of its pivot from the shank 37 and this boss extends upwardly when the shank drops. By pressing down on the boss, the shank 50 may be raised and confined within the slot 35 whereby the arm 14 may be swung to its open position, the shank passing between the ears 12 and the lugs 12'.

In using the wrench it is usually supported upon a carriage, as is shown in my 55 Letters Patent No. 1,481,158, or it is suitably suspended by a hanger, whereby it may be swung toward and away from the work. The arm 14 is swung to the open position 60 shown in dotted lines in Fig. 1, whereby the finger 16 is swung into the path of the work. The handle lever 18 is also swung to its open position as is shown in dotted lines 65 in Fig. 1. When the lever is thus swung the lug 30 of the dog 27 is engaged in the

notch 31, whereby the handle lever is held in its open position and the nose 33 is projected through the seat 11 of the yoke 10.

With the parts in the open position the yoke 10 is swung toward the work A, which 70 may be a rotary drilling pipe, tool joint, pipe coupling, or any other tubular member, in a vertical position. As the yoke straddles the work the finger 16 is engaged by the work and this swings the arm 14 to a 75 closed position. However the workman may grasp the handle 34 and swing the arm 14, and it is practical to eliminate the finger 16 and its function. When the seat 11 and the work engage, the latter will depress the nose 33 and swing the dog 27, whereby the lug 30 will be withdrawn from the notch 31 and the lever 18 thus released. The dog also functions to force the pipe into the 80 seat and to take up play, whereby the wrench 85 acts more quickly.

The handle lever 18 having been released may now be swung so as to receive the boss 21 in the seat 20 and to cause the lug 23 to 90 enter the recess 22. The closed position of the arm 14 is shown in full lines in Fig. 1 and in such position the latch 36 will have its lug 38 resting on the lower ear 12 (Fig. 2) behind the shoulder 12'. While the arm will thus be fastened against swinging open, 95 it will be free to swing inwardly against the work. By pulling the handle lever forwardly the boss 21 fulcrums in the seat and the lug 23 rides further into the recess. This 100 action swings the arm so that the yoke and arm are drawn snugly around the work and the dies 25 and 26 are caused to grip the work, with a minimum slippage. The seat and lug 23 swinging in an arc having a shorter radius than the arc in which the 105 boss 21 is swung, tend to exert a circumferential force on the arm and this acts to offset a crushing effect as well as counteracting any tendency of the ends of the yoke to 110 spread.

Various changes in the size and arrangement of the parts as well as modifications and alterations may be made within the scope of the appended claims.

What I claim, is:—

1. In a pipe wrench, a yoke having ears at its ends and provided with a gripping face, a handle lever pivoted to the ears at one end of the yoke, a gripping arm pivoted to the ears at the other end of the yoke, a shoulder on the ear at the end of the yoke to which the arm is pivoted, a latch pivoted to the arm and having its end located to engage the shoulder, and means on the handle lever for engaging and swinging the 120 arm after the latter is closed and latched.

2. In a pipe wrench, a yoke having an arcuate gripping face, a gripping arm pivoted on one end of the yoke, a handle pivoted on the other end of the yoke and having 125

means for engaging the arm for gripping a pipe, and a spring-pressed element mounted in the yoke for holding the handle in an open position and engaging the pipe received in the yoke.

3. In a pipe wrench, a rigid yoke having an arcuate gripping face, a gripping arm having an arcuate gripping face pivoted to one end of the yoke and having a boss on its free end, a handle pivoted on the outer end of the yoke and having a lug engaging over the boss of the arm for drawing the faces of the yoke and arm into gripping relation with a pipe, and a latch carried by the arm and co-acting with the yoke to hold the arm in its closed position.

4. In a pipe wrench, a yoke having an arcuate gripping face, a gripping arm pivoted to one end of the yoke and carrying a gripping die opposite the gripping face of the yoke and also having a boss, a latch carried by the arm and engaging the end of the yoke to which the arm is pivoted, and a handle pivoted to the other end of the yoke and having a lug engaging over the boss of the arm for moving the gripping die thereof into engagement with the pipe when the handle is swung.

5. A latching mechanism for a pipe wrench, comprising in combination with a yoke, a swinging gripping arm, and a gravity latch pivoted in the arm for engaging with one end of the yoke for limiting the swing of the arm.

6. In a pipe wrench, a rigid yoke having an arcuate gripping face, a handle lever pivoted to one end of the yoke having a projection with a comparatively short radius, and a swinging arm having an arcuate gripping face and pivoted to the other end of the yoke, the free end of the arm being directly engaged by the lever, whereby the face of the arm is caused to grip the pipe when the handle lever is swung, and means for fastening the lever in its open position released by the pipe received in the yoke.

7. In a pipe wrench, a yoke having an arcuate gripping face, an arm pivoted on one end of the yoke, a handle carried by

said arm, a latch carried by the arm handle and engaging the end of the yoke to which the arm is pivoted, a boss carried by the arm, a spring dog mounted in the yoke, and a handle lever having a lug engaging the boss for gripping a pipe.

8. In a pipe wrench, a rigid yoke having an arcuate gripping face, an arm pivoted to one end of the yoke and having an arcuate gripping face, a hand-hold on the arm, a boss on the free end of the arm, a handle pivoted on the other end of the yoke and having a lug for engaging the boss and moving the arm into gripping engagement with a pipe, and a latch co-acting with the end of the yoke on which the arm is pivoted for holding the arm in its closed position.

9. In a pipe wrench, a rigid yoke having an arcuate gripping face, an arm pivoted to one end of the yoke and having an arcuate gripping face, a handle extending from the pivot end of the arm, a boss on the free end of the arm, a handle lever pivoted to the other end of the yoke and having a lug for engaging the boss and moving the arm into gripping engagement with a pipe, and a latch mounted at the handle of the arm for engaging the yoke to lock the arm in its closed position.

10. In a pipe wrench, a rigid yoke having an arcuate gripping face, an arm pivoted to one end of the yoke and having an arcuate gripping face, a handle extending from the pivot end of the arm, a boss on the free end of the arm, a handle lever pivoted to the other end of the yoke and having a lug for engaging the boss and moving the arm into gripping engagement with a pipe, a latch mounted at the handle of the arm for engaging the yoke to lock the arm in its closed position, and a spring-tension dog mounted in the yoke for engaging and holding the handle lever in an open position, said dog being in the path of the pipe engaged by the yoke.

In testimony whereof I affix my signature.

NELSON K. SMITH.
